UNITED STATES PATENT OFFICE.

JACOB D. W. WILLIAMS, OF TABOR, NORTH CAROLINA.

DEVICE FOR TEACHING PENMANSHIP.

1,343,244.

Specification of Letters Patent. Patented June 15, 1920.

Application filed March 13, 1920. Serial No. 365,657.

To all whom it may concern:

Be it known that I, JACOB D. W. WILLIAMS, a citizen of the United States, and a resident of Tabor, in the county of Columbus and State of North Carolina, have invented certain new and useful Improvements in Devices for Teaching Penmanship, of which the following is a specification.

My invention relates to devices for teaching penmanship, and the purpose of my invention is the provision of a simple and efficient device of this character which exercises and trains the muscles to accurately perform the fundamental principles of penmanship.

I will describe one form of device embodying my invention and will then point out the novel features thereof in claims.

In the accompanying drawings:

Figure 1 is a view showing in top plan one form of device embodying my invention.

Fig. 2 is a view showing in bottom plan the device shown in Fig. 1.

Fig. 3 is a transverse sectional view taken on the line 3—3 of Fig. 1.

Referring specifically to the drawings and particularly to Fig. 2, B designates a board or plate form comprising a large section 15 and a small section 16, the latter being spaced from the former but rigidly connected thereto at its underside by strips 17 carrying feet 18 preferably formed of rubber which are designed to support the board in slightly elevated position to permit the requisite freedom of movement of certain of the movable members comprised in the device. The upper side of the board B is covered by a thin sheet S of metal or other suitable material which is bent along its longitudinal

edges and secured to the under side of the sections 15 and 16, as clearly shown in Fig. 2. This sheet S is provided with a slot 19 in which works a pin or projection 20 secured to a lever L. The lever L is arranged upon the under side of the board B at a point between the sections 15 and 16 and is pivoted at one end to the section 15 by an ear 21. The pin 20 is rigidly connected to the lever L at a point adjacent its free end so that when the pin is reciprocated within the slot 19, an oscillatory movement is imparted to the lever.

As shown in Figs. 1 and 3, the upper end of the pin 20 is journaled within a guide plate P arranged upon the upper side of the board B. The plate P in the present in-

stance is of ovate formation and is formed of transparent material such as celluloid or the like. As shown in Fig. 1, the pin 20 is connected to the plate P adjacent one of its ends, while adjacent the opposite end a crank C is connected thereto. The crank C is journaled in the section 15 of the board B and is connected to the plate P by a screw 22 in such manner that upon rotation of the crank a rotary movement is imparted to the plate, the pin 20 allowing this rotary movement but restricting the same in such manner that the plate is caused to describe an ovate movement. The crank is actuated through the medium of a handle 22 formed on its upper end which is adapted to be gripped by the operator. For varying the ovate movement of the plate P, the latter is provided with a plurality of openings 23 into any one of which may be inserted the screw 22. As shown in Fig. 3, the screw 22 is adjustable on and detachably connected to the crank so that it can be removed when changing the crank from one opening to another. As shown in Fig. 1, the openings 23 are disposed at various angles with relation to the pin 20 so that by changing the crank from one opening to another, the movement of the plate P can be varied to describe a figure of more or less ovate formation.

To vary the size of the oval described by a pencil, the crank C is provided with a series of openings 25 having screw threaded walls 26 so that any one of such openings can threadedly receive the screw 22, as shown in Fig. 3.

At a point between the crank C and the pin 20, the plate is provided with a series of perforations 24 and into any one of these perforations the point of a pencil is adapted to be inserted and held so that when the plate P is moved by the actuation of the crank C, the pencil point will be caused to move in the path of an oval. As shown in Fig. 3, the plate P is slightly spaced from the sheet S for the purpose of permitting the insertion of a sheet of paper between the two. With the sheet of paper disposed beneath the plate P, it is obvious that with a pencil held within one of the perforations 24, a figure of ovate formation will be described by the pencil upon the paper. The formation of the figure may be varied in accordance with the position of the pencil within the plate P, that is to say, that with the pencil in the opening nearest the pin 20,

a more decided oval will be described than with the pencil in the opening nearest to the crank C.

In the practical operation of the device, 5 the crank C is actuated by the teacher, while the pupil holds the pencil in vertical position through one of the openings 24 so that the pupil's arm is caused to describe an oval thereby exercising and training the muscles 10 of the hand and arm in the formation of such a figure. It is well known that the oval constitutes the fundamental figure in penmanship so that after a pupil's muscles have been trained to accurately form such 15 a figure, a great stride has been made toward teaching the pupil to write legibly and rapidly.

It is to be particularly noted that my device permits the accurate formation of an 20 oval by a pupil without subjecting the muscles of the arm and hand to any strain in retaining the pencil in proper position within the plate so that the necessary freedom of movement of the arm and hand is maintained while at the same time a guiding of 25 the two is merely effected. In all devices of this character with which I am familiar it is necessary to exert some lateral pressure upon the pencil to maintain it in proper 30 position. This naturally causes a tension upon the muscles of the arm and hand which necessarily means a tensioning of the muscles so that the requisite freedom of movement of the arm and hand cannot be secured, thus defeating the very purpose for 35 which it is intended.

Although I have herein shown and described only one form of device embodying my invention, it is to be understood that 40 various changes and modifications may be made herein without departing from the spirit of the invention or the spirit and scope of the appended claims.

• What I claim is:

45 1. A device of the character described comprising, a board having a slot therein,

a lever pivoted on the board and arranged on its under side, a projection working within said slot and operatively connected to said lever, a crank journaled in the 50 board, a handle formed on said crank, and a transparent perforated plate arranged upon the upper side of the board and connected to said pin and crank in such manner as to effect an ovate movement of the 55 plate when said crank is rotated.

2. A device of the character described comprising, a board, a plate having perforations formed therein to receive a pencil point, said plate being spaced from the 60 board to permit the insertion of a sheet of paper therebetween, and means carried by said board for effecting a movement of said plate to cause a pencil held within one of its perforations to describe an oval on the 65 sheet of paper.

3. A device of the character described comprising, a board including sections spaced apart from each other, a sheet of material covering the upper side of said 70 board and spanning the space between said sections, said material being provided with a slot in that portion which spans said sections, a lever pivoted to one of the sections and disposed at the under 75 side of the board, a pin carried by said lever and working within said slot, a transparent perforated plate arranged upon the upper side of said material and connected to said pin, and a crank adjustably connected to said plate, for the purpose described.

4. A device of the character described comprising, a board, a plate spaced from and movably supported on said board, said 85 plate being formed with perforations to receive a pencil, and means carried by said board for imparting an ovate movement thereto, said means being adjustably associated with the plate to vary the degree of 90 movement of the latter.

JACOB D. W. WILLIAMS.
